(57) **CLAIM**

The ornamental design for a lifting bracket for reinforced concrete, as shown and described.

DESCRIPTION

FIG. 1 is a front perspective view of a lifting bracket for reinforced concrete showing our new design.

FIG. 2 is a front elevational view thereof.

FIG. 3 is a bottom plan view thereof, the top plan view being a mirror image thereof.

FIG. 4 is a rear elevational view thereof; and,

FIG. 5 is a left side elevational view thereof, the right side elevational view being a mirror image thereof.
